UNITED STATES PATENT OFFICE.

FRANK A. BRENNER, OF SOUTH BEND, INDIANA, ASSIGNOR TO THE STUDEBAKER CORPORATION, OF SOUTH BEND, INDIANA, A CORPORATION OF NEW JERSEY.

VEHICLE CLOSURE.

Application filed May 18, 1925. Serial No. 31,063.

This invention relates in general to curtains, and particularly to curtains of that type which are wound up on a roller when in inoperative position, and more particularly to the application of such curtains to an open type automobile for the purpose of forming an enclosure for the sides of the same.

When two or more of such curtains are applied to each side of an automobile, it is preferable, for the sake of appearance and simplicity in use and construction, not to use any guiding post for the adjacent edges of adjacent curtains, but instead position the curtains so that their adjacent edges overlap to form a tight closure. Inasmuch as these curtains are universally constructed of fabric or other pliable material which is apt to stretch in use, and due to the fact that the pliable transparencies provided for windows is of a non-stretchable nature, the edges of the curtains become stretched a greater extent than the middle portion which carries the transparencies and consequently have a tendency to bag or sag, preventing the overlapping edges from lying tightly one against the other and allowing the ingress of the elements through the opening thus exposed into the interior of the automobile.

With the above in view it is the principal object of the present invention to provide means for preventing such curtain edges from stretching and sagging, whereby when they are in overlapping position they will lay against each other and effect a relatively tight closure.

Another object is to provide an edge of such curtains with a thin, metallic strip capable of being rolled with the curtain on to the curtain roller, and securing such strip to such edge whereby the strip, and not the fabric, will receive any strains exerted on the curtain.

Another object is to provide such a curtain with a relatively stiff cross or horizontal stiffening member in conjunction with a thin, flexible, non-stretchable vertical edge member.

A further object is to provide the lower corner of the edge of such a curtain, which is adapted to be received within a groove, with a thin, flat, reinforcing member to prevent tearing of such corner and to help it hold its shape.

The above being among the objects of the

present invention, the same consists of certain features of construction and combination of parts to be hereinafter described with reference to the accompanying drawing, and then claimed, having the above and other objects in view.

In the accompanying drawing which illustrates a suitable embodiment of the present invention, and in which like numerals refer to like parts throughout the several different views,

Figure 1 is a perspective view of the upper portion of an open type automobile to which the present invention is applied, one of the curtains being shown in full extended position and another in partly raised position.

Figure 2 is a fragmentary perspective view of a portion of the far side of the top of the automobile shown in Figure 1, the method of mounting the curtains therein being clearly shown.

Figure 3 is an enlarged broken view from the inside of one of the roller curtains in unrolled position, part of the fabric being broken away at different points to better illustrate the construction.

Figure 4 is a broken perspective sectional view taken on the line 4—4 of Figure 3, the thickness of the metallic strip being exaggerated to better show the construction.

Figure 5 is a broken perspective sectional view taken on the line 5—5 of Figure 3.

Figure 6 is a broken perspective sectional view taken on the line 6—6 of Figure 3.

In Figure 1 is shown an automobile of the open type having a body 10, and top 11 supported thereon by front supports 12 and rear supports 13. Supported within each side quarter of the top 11 by brackets such as 14, in the manner shown in Figure 2, are two curtains 15 and 16, each being independently supported on a spring controlled roller 17 of conventional construction so that each may be raised or lowered independently of the other. The front edge of the front curtain 15 is guided when in extended or operative position, as shown in Figure 1, or in partly operative position, by being slidably received in a vertically extending groove 18 (not shown) in the rear face of the front support 12, and the rear edge of the rear curtain 16 is guided in a like manner by being slidably received in a groove 19 in the front edge of the rear support 13. The cur-

tains 15 and 16 are so supported by their rollers 17 in the top 11 that the rear edge of the front curtain 15 overlaps the front edge of the rear curtain 16 to provide a tight joint 5 between the two curtains in order to prevent the ingress of the elements therethrough when they are in operative position. Permanent or removable auxiliary grooved posts extending between the body 10 and top 11 10 have been used at the adjacent edges of such curtains but they are objectionable due to the fact of their unsightliness when permanent, and due to the bother and trouble necessary to place them in position and to remove them when removable, and it has been 15 found more practical to eliminate them entirely.

The curtains themselves are formed of fabric, which may be coated by various conventional substances if desired, and each curtain is provided with flexible transparencies 19 of material such as celluloid, to provide windows therein. In the course of ordinary wear and tear on the usual type of 25 such curtains the fabric becomes stretched, and due to the fact that the transparencies are relatively non-stretchable, an excess in the length of the fabric occurs which causes the edges of the curtains to become loose or 30 to sag and to lose their tautness, whereby the overlapping edges no longer remain tight against one another when the curtains are down, but often leave gaps between them which are not only unsightly but which allow 35 the ingress of the elements therethrough. The present invention contemplates the elimination of such stretched condition of the fabric by securing in and to the vertical edge of the curtain a thin, non-stretchable strip 20 of material which may be readily wound up on the roller with the curtain and which will take the pull on the curtain, exerted in the operation of pulling it down to operative position or due to other 40 causes, and thus relieve the fabric of the tension, thus eliminating the cause of stretching.

The manner of constructing the curtain with such member inserted therein is clearly 50 shown in Figures 3 to 6 inclusive, which show its application to the curtain 16, Figure 3 being a view from the rear showing the manner of turning the edges of the fabric back on itself and the position of the 55 various members. The rear corner of the curtain is notched out to allow the lower edge to overlie the upper outer edge of the body 10 when pulled down to operative position. Two rigid transverse stiffening 60 members 21 and 22 are provided, the former at the lower edge of the curtain and the latter positioned somewhat above it, a generous portion of the lower edge of the fabric being turned back on itself to form a pocket 65 for the stiffening member 21 at the lower

edge of the curtain, and being sewed together immediately above the latter to hold it in position, and extending up over the stiffening member 22 on each side of which it is again sewed to hold the member 22 in 70 position. These stiffening members 21 and 22 hold the lower edge of the curtain 15 stiff and taut along their length. A piece of thin, stiff material 23 such as celluloid or sheet metal, is also sewed into the curtain directly above the notch in the lower rear corner of the curtain 16 and below the stiffening rod 22, to hold the corner stiff and prevent it from bending or tearing should it stick in the groove 18. The rear edge of the 80 curtain fabric is preferably turned back on itself and sewed, as shown, without the addition of any vertically extending non-stretching strip, as such strip has been found to be unnecessary at this edge due to the 85 fact that it is retained in the groove 18. The fabric at the forward edge of the curtain is also turned back on itself and sewed together, but as this edge is adapted to overlap the rear edge of the front curtain 15, it is 90 necessary to prevent its stretching as previously described, and it is at this edge that the non-stretching strip 20 is inserted within the pocket formed by turning the fabric back on itself at that point. The strip 20 is 95 preferably of thin spring metal such as the material from which clock springs are made and it is preferably riveted or otherwise secured to the fabric at different points along its length and to the cross stiffening members 21 and 22. Although the strip 20 must be thin enough and flexible enough to be readily wound up on the roller 17 with the curtain 16, I have found that it effectually 100 prevents stretching and consequent sagging of the edge of the curtain. When the rear edge of the front curtain is likewise provided with a strip such as 20, and the curtains 15 and 16 are properly constructed and hung so that their overlapping edges 105 lay one against the other, they will continue to remain in such position without sagging during the remainder of their use.

What I claim is:—

1. In combination with an automobile 115 provided with a top, and a curtain supported on a roller in the quarter thereof for providing a closure, means for preventing stretching and distortion of said curtain comprising a horizontal stiffening member adjacent the lower edge thereof, and a vertically extending non-stretchable member secured to a vertical edge thereof and to said stiffening member, said non-stretchable member being rollable on to said roller with 120 said curtain.

2. In combination with an automobile provided with a body, a top supported thereon by grooved supports, a plurality of rollers supported within said top, and a fabric 130

curtain provided with a flexible transparency secured at its upper edge to each of said rollers in overlapping relation, the vertical edges of said curtains adjacent said 5 supports being received in and guided in the grooves thereof and the opposite edges being unguided; horizontally extending stiffening bars secured to the lower edges of said cur-

tains, and flexible metallic strips secured to the unguided vertical edges of said curtains 10 and to said stiffening bars to prevent stretching of said curtains, said strips being windable on said rollers with said curtains.

Signed by me at South Bend, Indiana,
U. S. A., this 16th day of May, 1925.

FRANK A. BRENNER.
